UNITED STATES PATENT OFFICE.

WILLIAM H. JORDAN, OF BROOKLYN, NEW YORK, ASSIGNOR OF ONE-HALF TO CHRISTOPHER C. JORDAN, OF NEW YORK, N. Y.

COMMUTATOR-DRESSING APPARATUS.

Application filed September 17, 1921. Serial No. 501,442.

To all whom it may concern:

Be it known that I, WILLIAM H. JORDAN, a citizen of the United States, and a resident of the borough of Brooklyn, county of 5 Kings, city and State of New York, have invented a certain new and useful Commutator-Dressing Apparatus, of which the following is a specification.

The invention relates to an apparatus for 10 removing the strips of insulation from between the metallic bars of a commutator without dismantling the motor, or generator, of which the commutator forms a part, and is particularly designed for removing said 15 insulating strips in part preparatory to grinding the commutator to true the same.

When a commutator becomes untrue due 20 to uneven wear of the bars caused by the engagement of the brushes, or by pitting or of breaking down of the edges of the commutator bars, the usual practice is to grind the commutator without removing the armature from the machine.

In the grinding operation the insulation 25 between the bars, generally mica strips, will not be ground off flush with the cylindrical surface of the commutator, and in many cases it is not attacked by the grinding wheel or disc, but remains standing above the new 30 surfaces of the bars and prevents the same from being ground to true cylindrical form. The projecting insulation also prevents good contact of the brushes with the commutator and the latter quickly becomes worn due to 35 sparking and to blows given to it in its passage under the brushes.

The objects of the present invention are 40 to provide a device which is cheap to construct, which will not easily get out of order; which is simple to operate; by means of which the insulation, or as much thereof as is desired which may be quickly and cleanly removed from between the commutator bars 45 without injury to the latter; by means of which the depth to which the insulation is removed may be regulated; which may be guided in its passage along the commutator, and in which the guiding means may be adjusted to suit commutator bars of different 50 width.

These and further objects will more fully appear in the following specification and accompanying drawings considered together or separately.

One embodiment of the invention is illus-

trated in the accompanying drawings in which like parts in all of the several figures are designated by corresponding characters of reference, and in which—

Fig. 1 is a side elevation of an apparatus 60 embodying the invention.

Fig. 2 is an end elevation of the same.

Fig. 3 is a top plan view of the same illustrating one form of driving means.

Fig. 4 is a section on the line 4—4 of Fig. 65 3, and

Fig. 5 is a top plan view of a modified form of drive.

In the embodiment of the invention illustrated 1 designates a frame having an elongated cylindrical bearing 2 at about its central portion, said bearing having its outer periphery screw threaded as shown. The frame is provided with a handle 3 arranged perpendicular to the bearing 2. 75

Overhanging the bearing, and at opposite sides thereof are two flanges 4 and 5 preferably integral with the carriage 1. The flange 4 is provided with two slots 6 extending in the direction of the radial line of the bearing 2, and the flange 5 is provided with two similar slots 7. 80

Threaded on the bearing 2 is a nut 8 having a milled head 9 at its outer extremity. The nut is provided with a shoulder 10, and 85 a collar 11 is secured to the inner extremity of the nut. Journalled in the groove formed between the shoulder 10 and the collar 11 is a carriage 12 having a flange 13 projecting over the flange 4 of the frame 1, and a flange 90 14 projecting under the flange 5. Each of the flanges 13 and 14 is provided with a pair of perforations 15, and each perforation corresponds in position with one of the slots 6 and 7. The slots 6 and 7, and the perforations 15 are so disposed relatively to the bearing 2 that two slots and two bearings, all in alinement, are disposed at diametrically opposite sides of the bearing. 95

Extending through the alined slots and 100 perforations at each side of the bearing is a screwthreaded spindle 16 each encircled by a coil spring 17 and each provided with two milled nuts 18 and 19. The nut 19 acts as an abutment for the spring 17 of that 105 spindle and the opposite end of the spring abuts against the flange 4 of the carriage. The nut 19 also acts as an adjustable stop for limiting the movement of the spindle in one direction, and the nut 18 acts as an ad- 110

justable stop for limiting the movement of the spindle in the opposite direction.

Secured to the lower ends of the spindles 16 is a bar 20 having its lower edge preferably rounded, and provided with a longitudinal rib 21 also preferably rounded.

Mounted in the bearing 2 is a shaft 22 carrying at one end a circular saw 23 secured in position by means of a nut 24 or otherwise. The shaft 22 is provided, on the opposite side of the bearing with a coupling 25 by means of which a flexible shaft 26 may be attached thereto. The shaft 26 may be attached directly to the armature shaft of a motor 27, but preferably it is driven from the commutator shaft through reduction gearing 28, as shown in Fig. 3.

In the modification shown in Fig. 5 the saw shaft 22 is provided with a bevel gear 29 with which engages a bevel pinion 30 fast to the shaft 31 of a motor 32 carried by the handle 33.

The operation of the embodiment of the invention illustrated in Figs. 1, 2, 3 and 4 is as follows:

The motor 27 is set up at a convenient distance from the machine the commutator of which is to be acted on. The insulation 34 between two of the commutator bars 35 is removed to the desired depth by any suitable means.

The nut 8 is now manipulated to move the carriage 12 longitudinally of the shaft 22, the slots 6 and 7 permitting of such movement, until when the rib 21 of the guide bar 20 is placed in a slot formed by the removal of the insulation 34 the saw will be directly over an uncut strip of insulation.

The handle 3 is then grasped by the operator the motor is started, and the forward end of the rib 21 is placed in the outer extremity of the more or less open commutator slot. The apparatus is now pressed down on the commutator until the flange 14 engages the nuts 18 which will limit the downward movement and determine the depth to which the insulation is to be removed by the saw.

The device is now moved inward along the cylindrical surface of the commutator, and the saw will remove the insulation from that slot to the depth desired. The body of the guide block 20 is of such width that it cannot enter the slots and will prevent cutting of insulation to too great a depth. The rib 21 acts to guide the device in a straight line, and there will be no danger of the saw injuring the bars of the commutator.

The rounded lower edge of the guide block 20, and the rounded form of the rib 21 will permit of proper engagement with the tops of the bars 35, and with the open slots, notwithstanding the fact that the

saw 23 and the spindles 16 are disposed at an angle to each other due to the difference in the radial angles of the slots of the commutator.

When the insulation has been removed from one slot by the saw, that slot becomes the guide for the guide bar, and the operation is repeated until the insulation has been removed, in part, from all of the commutator slots. Preferably the commutator to be acted on is rotated between the cutting operations to bring the slot to be acted on to the top.

The depth of cut of the saw is limited by the distance between the nuts 18 and the flange 14, and said distance may be regulated by screwing the nuts toward or away from the flange.

As the bars of different commutators differ in width the guide 20 must be adjustable longitudinally of the shaft 22 in order that the guide always may enter an open slot when the saw is in position over a filled slot. By rotating the nut 8 the guide may be moved toward or away from the saw whereby the device may be adjusted to operate on commutators of varying width of bars.

In accordance with the provisions of the patent statutes the principle of the invention has been described, together with the apparatus which is now considered to represent the best embodiment thereof, but it is desired to have it understood that the apparatus shown is merely illustrative, and that the invention may be carried out in other ways.

The invention having been described, what is claimed and desired to be secured by Letters Patent, is:

1. A device of the character described, comprising a saw, means for driving the saw, cushioned means for regulating the depth of cut of the saw, and means for adjusting the regulating means.

2. A device of the character described, comprising a circular saw, means for rotating the saw, cushioned means for regulating the depth of cut of the saw, and means for adjusting the regulating means.

3. A device adapted to remove insulation from slots between commutator bars, comprising a circular saw, means for rotating the saw, means engaging a commutator bar for limiting the depth of cut of the saw, and means engaging a slot in the commutator parallel to that engaged by the saw for guiding the saw.

4. A hand-operated power driven device adapted to remove insulation from the slots between commutator bars, comprising a circular saw, power means for rotating the saw, said saw being manually movable longitudinally of the commutator, an element adapted to engage the commutator for lim-

itizing the depth of cut of the saw, and means carried by the element for engaging a slot parallel to that engaged by the saw for guiding the saw in its travel over the commutator.

5. A device of the character described, comprising a power driven circular saw mounted on a shaft and adapted to remove, partially at least, a strip of insulation between two bars of a commutator, a bearing on the device, said shaft rotating in the bearing, a nut on the bearing, a carriage engaging the nut, the latter being rotatable relatively to the former, movable spindles carried by the carriage, springs on the spindles, nuts on the spindles for limiting the movement of the spindles in one direction, nuts on the spindles for limiting the

movement thereof in the opposite direction, a guide bar carried by the spindles and a 20 longitudinal rib on the guide bar.

6. A device for removing insulation between bars of a commutator, comprising a circular saw and means for rotating the same, adjustable, spring cushioned 25 means engaging a commutator bar for limiting the depth of cut of the saw, said limiting means being adjustable toward and away from the saw.

This specification signed and witnessed 30 this 16th day of September, 1921.

WILLIAM H. JORDAN.
